UNITED STATES PATENT OFFICE.

WILLIAM J. LUTTON, OF PATERSON, NEW JERSEY.

LET-OFF MECHANISM FOR LOOMS.

Application filed March 5, 1926. Serial No. 92,571.

This invention relates to let-off mechanism for looms, with the object in view of providing means for automatically maintaining a uniform tension on the warp threads throughout the entire width of the shed as 5 the threads are let off step by step from the warp beam.

Another object is to provide means for mounting a warp beam which may be moved vertically in the frame of the loom, whereby 10 the weight of the warp beam will apply tension to the warp threads.

Another object is to provide a vertically movable warp beam arranged to receive a weight bar for applying additional weight 15 to the beam and tension to the warp threads.

Another object is to provide mechanism 20 frictionally engaging the warp beam for arresting the rotary movement thereof, and means controlled by the vertical movement of the beam for releasing said mechanism.

Another object is to provide a manually 25 operated device for temporarily supporting the warp beam and thereby relieving the tension on the warp threads at any moment when it is so desired.

Another object is to provide certain improvements in the form, construction and arrangement of the several parts, whereby 30 the above named and other objects may effectively be attained.

A practical embodiment of my invention is represented in the accompanying drawings, in which—

Fig. 1 represents a plan view of so much 35 of a loom as is required to illustrate an embodiment of my invention.

Fig. 2 represents an end elevation of the same.

Fig. 3 represents a vertical section taken 40 in the plane of the line III—III of Fig. 2, looking in the direction of the arrows.

Fig. 4 represents a side elevation of the parts shown in Fig. 1.

Fig. 5 represents a detail vertical section 45 taken in the plane of the line V—V of Fig. 4, looking in the direction of the arrows, and

Fig. 6 represents a detail vertical section 50 taken in the plane of the line VI—VI of Fig. 2, looking in the direction of the arrows.

The frame of the mechanism is denoted by 1 and provided with flanges 2 by which it may be secured to the frame 3 of the loom by bolts 4. A warp beam 5 is supported on 55 a shaft 6 journaled in hangers 7, 8 adjust-

ably mounted on arms 9, 10 of a yoke 11. This yoke 11 has reduced ends 12, 13 arranged to be journaled in bearings 14, 15 fixed to the frame 1. The hanger 7 is provided with an elongated slot 16 arranged to receive a bolt 17 carried by the arm 9 of the yoke, and by which bolt the hanger may be adjusted vertically and secured to the arm. The lower end of the hanger 7 has an open bearing 18 arranged to receive one end 60 of the shaft 6 of the warp beam.

The hanger 8 is similarly provided with an elongated slot 19, and the arm 10 with a bolt 20, which secures the hanger 8 in vertical adjustment on the arm. The lower end 70 of the hanger 8 also has an open bearing 21 arranged to receive the opposite end of the shaft 6 of the warp beam.

The shaft 6 of the warp beam is extended a distance beyond the bearings 18, 21 of the 75 hangers 7, 8 so that a weight bar 22 may be suspended therefrom by means of links 23, 24. This weight bar 22 is arranged to receive a series of weights 25, the number of weights located on the bar being dependent 80 upon the tension which is desired to be placed upon the warp threads.

The warp beam 5 includes mechanism for arresting the rotary movement thereof, which mechanism comprises a drum 26 and 85 two U-shaped straps 27, 28. One end of the strap 27 has a short extension 29 while the other end has a long extension 30. The strap 28 also has a short extension 31 and a long extension 32. The short extensions 90 29 and 31 are held in position by means of a bolt 33 and nut 34. The long extension 30 is arranged to be brought toward the extension 32 by means of an eccentric cam 95 35 having a shaft 36 journaled in bearings 37, 38 secured to the extension 32 by a bolt 39. The cam 35 is oscillated by means of an arm 40 fixed to the shaft 36.

A spring 41 is disposed between the arm 40 and a pin 42 carried by a bracket 43 secured to the arm 10 of the yoke. This spring 41 tends to pull the arm 40 upwardly so that the cam 35 will force the extension 30 toward extension 32, which movement of the extension 30, will cause the linings 44, 45, of leather or other suitable material, fixed to the straps 27, 28, to frictionally engage the drum 26 and hold the warp beam against rotation.

The arm 40 is limited in its movement by 110

means of a lug 46 which extends laterally from the arm 40 into position to engage the frame 1.

Fixed to rotate with the warp beam 5 is a 5 brake drum 47. A band brake 48 of leather or other suitable material is secured to one end of a bar 49 and after passing around the drum 47, the opposite end is attached to a bolt 50, the threaded end of which extends 10 through a hole in the bar 49 and is provided with nuts 51, 52 for adjusting the frictional contact of the brake 48 on the drum 47.

The warp beam 5 together with the yoke and weight bar with the weights thereon 15 may be sustained at any time in the desired elevation by means of a link 53, one end of which is pivoted at 54 to the end of the arm 9 of the yoke, while the other end of the link has a bolt 55 arranged to extend 20 through a slot 56 in the frame 1. The threaded end of the bolt is provided with a tail nut 57 which serves to draw and lock the link 53 and frame together, thereby securing the arm 9 of the yoke against movement. By locking the arm 9 to the frame 25 the weight of the warp beam and its adjacent mechanism on the warp threads 58 is relieved.

The warp threads 58 carried by the warp 30 beam 5 are arranged to pass upwardly over the warp guide roller 59 journaled in uprights 60, 61, adjustably mounted on the frame 1 by means of bolts 62, 63. The warp threads pass from the guide roller 59 over 35 and under spreaders 64, 65 through the usual heddles and reeds (not shown).

The outer end of the extension 32 is disposed in position to bear upon the yoke 11 and hold the straps 27, 28 against rotation 40 on the drum 26 of the warp beam 5.

The outer end of the brake band 48 is also arranged to rest upon the yoke to prevent the same from rotating with the drum 47 on the warp beam 5.

45 While I have only shown a link 53 connected to the arm 9 of the yoke 11 and carrying a bolt 55 and tail nut 57 arranged to slide in a slot 56 of the frame 1 to hold the beam and its mechanism against movement, 50 I wish it understood that the arm 10 may also be provided with a similar link and bolt arranged to slide in a slot 66 in the frame 1.

In operation, assuming the warp beam 55 has been secured in the arms 9, 10 of the yoke 11, the necessary number of weights 25 added to the weight bar 22, the brake band 48 and straps 27, 28 adjusted and placed under such restraint as found desirable, the weaving 60 will gradually lift the warp beam 5 and its weights together with the arms of the yoke as the warp threads are taken up. This upward movement of the warp beam 5 will bring the lug 46 on the arm 40 into engagement with the frame 1, whereupon the fur-

ther upward movement of the beam will hold the arm 40 and cause the cam 35 to change its position with respect to the extension 30 of the strap 27. As the cam 35 changes its position, the extension 30 will be 70 free to move away from the extension 32 of the strap 28, which movement will release the frictional contact of the straps 27, 28 on the drum 26, and in consequence thereof the beam, due to its weight, will begin to 75 swing downwardly by gravity and rotate to let off the warp threads wound thereon.

This downward movement of the beam will continue until the lug 46 has been moved away from the frame 1 so that the spring 41 80 may exert its power to rock the arm 40 and hence the cam 35. In rocking the arm and cam, the extension 30 will be again forced toward the extension 32 and the straps 27, 28 caused to grip the drum 26, which thereby arrests the rotary as well as the downward movement of the beam. It will be understood that the link 53 will also move with the arm 9 and the bolt 55, carried by the link 53, will be free to slide in the slot 56 in the frame, and at any time the warp beam and its adjacent mechanism may be held in the desired position by screwing the tail nut 57 on the bolt 55 which will draw the link 53 against the frame 1 and lock the same against movement. By locking the link to the frame, the yoke with its arms and beam will be held against movement, in which position the tension on the warp threads will be relieved.

The tension on the warp threads may be reestablished and the parts again resume their respective positions by un-screwing the tail nut on the bolt, thereby releasing the link. When the link 53 and bolt are released the mechanism is free to be actuated by the weaving operation.

It is obvious that various changes may be resorted to in the form, construction and arrangement of the several parts without departing from the spirit and scope of my invention; and hence, I do not intend to be limited to the particular embodiments herein shown and described except as they may be included in the claims.

What I claim is:

1. In a loom, a frame, a warp beam vertically movable in said frame, mechanism frictionally engaging said beam for arresting the rotary movement thereof, and means for releasing said mechanism, said means normally engaging the mechanism for holding the beam and arranged to be brought into contact with the frame for actuating it by the vertical movement of the beam.

2. In a loom, a frame, a warp beam vertically movable in said frame, mechanism frictionally engaging said beam for arresting the rotary movement thereof, means for releasing said mechanism, said means nor-

- 5 mally engaging the mechanism for holding the beam and arranged to be brought into contact with the frame for actuating it by the vertical movement of the beam, and a 55
 5 spring coacting with the means for returning it to its normal position and actuating the mechanism to arrest the rotary movement of the beam.
- 6 3. In a loom, a frame, a yoke pivotally mounted therein, a warp beam carried by 10 said yoke, said beam being arranged to carry and apply tension to the warp threads, mechanism frictionally engaging the beam for arresting the rotary movement thereof, 15 and means for releasing said mechanism, said means normally engaging the mechanism for holding the beam and arranged to be brought into contact with the frame for actuating it by the vertical movement of the 20 beam.
- 7 4. In a loom, a frame, a yoke pivotally mounted therein, a warp beam carried by said yoke, said beam being arranged to carry and apply tension to the warp threads, mechanism frictionally engaging the beam for arresting the rotary movement thereof, means for releasing said mechanism, said means normally engaging the mechanism for holding the beam and arranged to be brought into 25 contact with the frame for actuating it by the vertical movement of the beam, and a spring coacting with the means for returning it to its normal position and actuating the mechanism to arrest the rotary movement of the beam.
- 8 5. In a loom, a frame, a yoke pivotally mounted therein, a warp beam carried by said yoke, said beam being arranged to carry and apply tension to the warp threads, mechanism frictionally engaging the beam for arresting the rotary movement thereof, means for releasing said mechanism, and a device coacting with the frame and yoke for temporarily locking the yoke to the frame 40 thereby supporting the beam and relieving the tension on the warp threads.
- 9 6. In a loom, a frame, a yoke pivotally mounted therein a warp beam carried by said yoke, said beam being arranged to carry and apply tension to the warp threads, mechanism frictionally engaging the beam for arresting the rotary movement thereof, means for releasing said mechanism, and a 45 manually operated device coacting with the frame and yoke for temporarily locking the yoke to the frame thereby supporting the beam and relieving the tension on the warp threads.
- 10 7. In a loom, a frame, a yoke pivotally mounted therein, a warp beam carried by 50 said yoke, said beam being arranged to carry and apply tension to the warp threads, mechanism frictionally engaging the beam for arresting the rotary movement thereof, and means for releasing said mechanism, said means comprising a cam carried by and disposed to engage the mechanism, and an arm on said cam arranged to be brought into contact with the frame for actuating the 55 cam to release the mechanism. 70
- 11 8. In a loom, a frame, a yoke pivotally mounted therein, a warp beam carried by said yoke, said beam being arranged to carry and apply tension to the warp threads, mechanism frictionally engaging the beam 75 for arresting the rotary movement thereof, and means for releasing said mechanism, said means comprising a cam carried by and disposed to engage the mechanism, and an arm on said cam arranged to be brought into contact with the frame for actuating the cam to release the mechanism, the movement of said arm being controlled in one direction by the vertical movement of the beam. 80
- 12 9. In a loom, a frame, a yoke pivotally mounted therein, a warp beam carried by 85 said yoke, a weight bar suspended from said beam for applying tension to the warp threads, mechanism frictionally engaging the beam for arresting the rotary movement thereof, and means arranged to be brought into contact with the frame for releasing 90 said mechanism.
- 13 10. In a loom, a frame, a yoke pivotally mounted therein, a warp beam carried by 95 said yoke, a weight bar suspended from said beam for applying tension to the warp threads, mechanism frictionally engaging the beam for arresting the rotary movement thereof, and means arranged to be brought 100 into contact with the frame for releasing said mechanism, said means being controlled in one direction by the vertical movement of the beam.

In testimony, that I claim the foregoing as my invention, I have signed my name this 2nd day of March, A. D. 1926.

WILLIAM J. LUTTON.
